Primary Examiner — Daniel J Domino*(74) Attorney, Agent, or Firm* — Fountainhead Law Group P.C.(57) **CLAIM**

We claim the ornamental design for a display screen or portion thereof with a graphical user interface, substantially as shown and described.

DESCRIPTION

The FIGURE is a front view of a display screen or portion thereof with graphical user interface showing our new design.

The outermost broken line shows an environment, whereas the remaining broken lines show a display screen and elements of a graphical user interface. None of the broken lines form part of the claimed design.
